UNITED STATES PATENT OFFICE

NORRIS F. MCNAUGHT AND EDWARD HENRY PETERSON, OF CHICAGO, ILLINOIS, AS
SIGNORS TO DURO METAL PRODUCTS COMPANY, OF CHICAGO, ILLINOIS, A CORPORA-
TION OF ILLINOIS

RATCHET LEVER

Original application filed October 8, 1928, Serial No. 311,026. Divided and this application filed April 30,
1930. Serial No. 448,463.

The present invention relates to ratchet levers, and is particularly concerned with ratchet levers adapted to be used as wrenches.

One of the objects of the invention is the provision of an improved ratchet lever assembly in which the wrench is positively connected to the handle and in which no springs are required for actuating the pawl.

Another object is the provision of a ratchet lever in which the pawl is automatically and positively moved into either engaging or releasing position by movement of the handle.

Another object is the provision of a ratchet wrench in which the connection between the wrench and handle is controlled by the movement of the handle and in which the force exerted upon the handle is utilized to actuate the pawl into the firmer engagement with the wrench.

Another object is the provision of a ratchet wrench which is more durable, more simple and more economically manufactured than the wrenches of the prior art.

Other objects and advantages of the invention will be apparent from the following description and from the accompanying drawings, in which similar characters of reference indicate similar parts throughout the several views.

The present application is a division of prior application Serial No. 311,026, filed October 8, 1928, on Ratchet levers.

Referring to the drawings,

Fig. 1 is a plan view of a ratchet wrench with the pawl and ratchet member shown in released or non-engaging position;

Fig. 2 is a view similar to Fig. 1 with one of the plates of the body member removed, showing the pawl in engaging positions;

Fig. 3 is a sectional view taken on the line 3—3 of Fig. 2.

Referring to the drawing, the ratchet lever or wrench, which is indicated in its entirety at 10, preferably includes a supporting or body member 11, a rotatable member 12, a pawl 13 and a handle 14.

The rotatable ratchet member 12 may consist of any form of wrench, including members having projecting wrench parts as distinguished from a socket, and the present em-

bodiment consists of a round metallic member provided with a plurality of teeth 15 located on its periphery and having a non-circular socket 16 axially located in its body. The rotatable member 12 is preferably formed with cylindrical portions 17 and 18 of a diameter less than that at the teeth 15, thereby providing annular shoulders 19 and 20 which may serve as thrust bearings to retain the rotatable member in its support, and the cylindrical surfaces 17 and 18 form journals for the same.

The ratchet wheel 12 may be constructed by casting the same of steel or other durable metal, and all of the parts of the ratchet wrench are preferably constructed of steel. The body member 11 preferably comprises a pair of steel plates 25 and 26 which are rounded at both ends 27 and 28 to remove sharp corners and tapered as at 29 to reduce the size of the plates and save material where it is not required.

Each of the plates 25 and 26 is provided with an enlarged circular aperture 30 adapted to serve as bearings for the journals 17 of the rotatable member 12, the apertures 30 being located to register with each other adjacent the enlarged end of the plates 25 and 26. The plate 26 is also provided with a pair of apertures 31 and 32 adapted to receive the bolts 33 and 34, and the plate 25 is provided with apertures of reduced size adapted to receive the threaded ends 37 and 38 of the bolts 33 and 34.

The bolts 33 and 34 are preferably formed with the cylindrical portions 39 and 40 adapted to serve as pivot posts for the pawl 13 and handle 14, respectively, and by providing reduced threaded portions 37 and 38, annular shoulders 41 and 42 are formed upon the bolts for engagement inside the plate 25, whereby the nuts 43 and 44 may be screwed tightly against the plate 25 without pinching the pawl or handle. In other words, this construction enables the plates 25 and 26 to be secured in spaced relation, permitting free movement of the pawl and handle.

The handle 14 preferably comprises a stock bar of steel having the edges rounded to protect the handle of the user and having sharp

corners removed. The bar 14 which comprises the handle is preferably of a thickness which will fit between the plates 25 and 26 with sufficient play for free movement, and 5 the bar is provided at one end with a transverse bore adapted to rotatably receive the cylindrical portion 40 of the bolt 34.

The body member 11 may comprise plates 25 and 26 identical in form to reduce the 10 number of different parts and decrease the cost of manufacture, both of the plates being provided with the bearing apertures 30 for the rotatable member 12, and with apertures 31 and 32 of the same size. The bolts 33 and 15 34 may comprise members having an enlarged cylindrical surfaces 39 and 40 and reduced end portions 58 and 59 adapted to be received in the apertures 31 and 32 of the plates 25 and 26. The cylindrical portions 58 and 20 59 of the bolts may be riveted over outside the plate 26, thereby permanently securing the plate to the bolts 33 and 34, and the bolts may be provided with reduced threaded ends 37 and 38 adapted to receive nuts 43 and 44 for 25 clamping the plate 25 between the nuts and the shoulders 41 and 42.

The wrench member of this embodiment has been provided with a square socket 16, and the ratchet wheel 12 of this embodiment is 30 preferably provided with a plurality of teeth 15, whose sides 23 and 24 are substantially the same slope.

The pawl 13 is provided with a tooth 55 adapted to engage between the teeth 15 on the 35 ratchet member 12, and the pawl is pivotally supported upon the bolt 33.

The cam surface on the pawl 13 may comprise a flat plane edge 52 while the cam surfaces on the handle 14 may comprise two relatively 40 flat edges 47 and 48 at an obtuse angle to each other with a slight tolerance between the apex 60 of the angle and the surface 52 of the pawl.

The operation of this embodiment is as follows: When the handle 14 is moved in a counterclockwise direction, the pawl 13 is disengaged from the ratchet member 12, and when the handle 14 is moved in the opposite direction, the pawl 13, is moved into engagement with ratchet member 12, by the handle 50 14. It should be noted that when the handle 14 is rotated counterclockwise in Figures 1 and 2, the cam surface 47 on the handle engages the flat surface 52 on the pawl 13 at a point 61 above the line of centers of the bolts 33 and 34, thereby rotating the pawl 13 in a counterclockwise direction. In this embodiment, therefore, the handle and pawl move in 55 the same direction to disengage the pawl from the teeth 15. When the handle 14 is moved in the opposite direction, or clockwise, the surface 47 recedes from the surface 52, but the surface 48 engages the surface 52 on the pawl 60 below the line of centers of bolts 33 and 34,

and rotates the pawl 13 clockwise, also bringing the pawl into the position of Figure 3.

The cam and handle are very economically manufactured, as they require very little machine work, and it is only necessary to remove a portion of the straight end of a bar to form the surface 47, while the surface 52 may be formed in cutting the material of which the pawl is formed into proper lengths. The pawl and lever of this embodiment are also 70 reversible relative to the ratchet wheel 12 in the assembly of the device, thereby simplifying the assembly, as there is less possibility of assembling parts in the wrong position. It should also be noted that when the tooth is 75 in the engaging position, the surface 48 cooperating with the pawl provides a stop member, preventing further movement of the handle relative to the wrench member and body, and when the pawl is in releasing position of Fig. 1, the surface 47 acts as a stop member to prevent further movement of the handle relative to the body in a counter-clockwise direction.

It will thus be observed that we have 80 invented a novel ratchet lever or wrench in which the pawl is positively actuated into engaging or non-engaging position by movement of the handle, thereby eliminating the necessity of any springs and 85 eliminating the drag between the pawl and ratchet which prevents the free return of the handle in the devices of the prior art.

Our ratchet wrench is also more positive in its action and durable in its construction, and 90 it comprises a new combination of elements which cooperate in an entirely novel manner to produce this result.

While we have illustrated and described a specific embodiment of our invention, many 95 modifications may be made without departing from the spirit of the invention, and we do not wish to be limited to the precise details set forth, but desire to avail ourselves of all changes within the scope of the appended 100 claims.

Having thus described our invention, what we claim is new and desire to secure by Letters Patent of the United States, is:

1. In a ratchet wrench, the combination of 115 a sheet metal bar forming a handle, a shoulered bolt passing through said handle, a pair of elongated plates carried by said bolt and spaced by the shoulders thereof, a pawl pivotally mounted between said plates, cooperating cam surfaces on said pawl and handle, and a toothed ratchet member carried by said plates to be actuated by said pawl and handle, the pivotal axes of said handle, pawl and ratchet member being located in substantial 120 alignment.

2. In a ratchet lever, the combination of a pair of plates, having registering apertures forming bearings for a ratchet member, a ratchet member having a plurality of teeth, 130

and having a trunnion formed at each end, said trunnions being rotatably mounted in said bearings, a pawl member pivotally mounted between said plates, and a handle member comprising a stock metal bar pivotally mounted between said plates, one of said latter two members having a flat end and the other of said latter two members having surfaces for engaging said flat end, one of which is spaced from said flat end when the other of said cooperating surfaces is in engagement with said flat end, whereby said handle is adapted to control the engagement of said pawl with said ratchet member.

15 3. In a ratchet lever, the combination of a supporting body a rotatable member having a ratchet formation thereon and having a plurality of shoulders on its periphery for rotatably mounting the ratchet on said body, a pawl member movably mounted on said body, a handle member movably mounted on said body for controlling said pawl member, said handle member and pawl member having cooperating flat end surfaces arranged with clearance in predetermined positions whereby said handle may actuate said pawl to tooth engaging position.

In witness whereof, we hereunto subscribe our names this 28th day of April, 1930.

30 NORRIS F. McNAUGHT.
